UNITED STATES PATENT OFFICE.

JOSEPH F. JOY, OF PITTSBURGH, PENNSYLVANIA, ASSIGNOR TO THE JEFFREY MANUFACTURING COMPANY, OF COLUMBUS, OHIO, A CORPORATION OF OHIO.

MINING AND LOADING MACHINE.

Application filed October 17, 1916, Serial No. 126,150. Renewed March 18, 1921. Serial No. 453,477.

To all whom it may concern:

Be it known that I, JOSEPH F. Joy, a citizen of the United States, residing at Pittsburgh, in the county of Allegheny and 5 the State of Pennsylvania, have invented certain new and useful Improvements in Mining and Loading Machines, of which the following is a specification, reference being had therein to the accompanying drawing.

10 The present invention relates to certain new and useful improvements in mining machines of the class which is adapted to form a kerf in the coal body to facilitate breaking the coal from its natural bed, and 15 after the coal is broken down, to gather the broken coal into cars for transportation from the mine.

The especial object of the invention is to provide an improved arrangement of 20 parts comprising cutting mechanism adapted to first form a kerf at the base of the coal body, and after the coal is broken down by any preferred means, such as by blasting, to gather the broken fragments from 25 the floor of the mine to a suitably disposed conveyor to be loaded into conveniently placed cars for transport from the mine.

The devices by which I attain this object are fully set forth in the following specification and illustrated in the accompanying drawings of which—

Fig. 1 is a plan view of the preferred embodiment of my invention, certain parts being broken away to reveal other parts.

35 Fig. 2 is a section taken along the line 2—2 of Fig. 1.

Fig. 3 is a section taken along the line 3—3 of Fig. 1.

40 Figs. 4, 5, 6, 7, and 8 are diagrammatic figures showing the methods of operation of the machine.

Like numerals refer to similar parts in the several figures.

As shown in the drawing the numeral 1 45 indicates the main frame casting upon which the several operative parts of the machine are supported. This main frame casting is shaped to form a sole plate 2 adapted to rest upon and slide over the floor 50 of the mine. Centrally positioned in the main frame 1, and extending longitudinally thereof, is the conveyor 3 by which the

coal is transferred to conveniently placed cars at the rear of the machine for transportation from the mine. Formed at the 55 forward part of the main frame 1, one on either side of the conveyor, are two housings 4 each of which supports a cutter arm 5 pivoted for rotation in horizontal planes. As both of these housings and the associated 60 parts are alike, a description of one applies to both. Formed in the housing casting is a hub 6 having a central aperture 7 in which is journaled the vertical shaft 8. To the lower end of the shaft 8 is secured a sprocket 65 wheel 9 which engages the cutter chain 10 to drive it. The cutter chain 10 is of well known construction, adapted to travel along the edges of the cutter arm 5, and is provided with renewable cutter bits 11 which 70 are so disposed that their cutting edges are presented to cut the coal as the chain 10 travels rearwardly along the outer edge of the cutter arm. Attached to the shaft 8, above the journal bearing 7, is a worm gear 75 12 which is engaged by the worm 13 formed integral with the worm shaft 14 horizontally mounted in bearings 15 of the housing 4. A cover plate 16 attached to the housing casting 4 encloses the worm and 80 worm wheel and in this plate is formed a journal bearing 17 which affords additional support for the vertical shaft 8. The cutter arm 5 is of well known construction and is attached by suitable bolts 18 to yoke casting 19 in which is formed a journal bearing 20 rotatably mounted upon the outer surface of the hub 6. On the yoke 19 is formed a circular flange 21 to which is secured a bearing ring 22, concentric with the shaft 8. This bearing ring 22 engages the upper 85 surface of a circular flange 23 of the housing casting to support the cutter arm 5 for free rotation about the shaft 8. The outer edges of the bearing ring 22 and flange 21 are shaped to form a grooved sheave 24 adapted to engage the feed rope 25 as will later appear. Formed on the housing casting is a lug 26 pierced vertically by an aperture 27 through which the pin 28 is 90 adapted to be thrust to engage a registering aperture 29 in the yoke 19 to lock the cutter arm 5 against rotation. A projection 30 is formed on the yoke casting 19 to which

the feed rope 25 may be attached to cause the rotation of the cutter arm 5 as will be fully explained.

Mounted upon the rearward part of the main frame 1 is a motor 31 by which power is supplied to actuate the several elements of the machine. The motor 31 is provided with a pinion 32 which engages with a spur gear 33 attached to a power shaft 34 extending transversely of the machine and supported in bearings 35 of the main frame. At each end of the shaft 34 is fixed a bevel gear 36, in engagement with a similar gear 37 attached to the shafts 38 extending longitudinally of the machine. At one end each shaft 38 is supported in a bearing 39 of the main frame, and at the other end in bearings 40 of the housing castings 4. The shafts 38 are adapted to be connected, through suitable clutch mechanism inside the housings 4, and controlled by the levers 41, with the worm shafts 14 to drive the cutter chains 10.

Bodily movement of the machine relative to the coal face, and also rotation of the cutter arms 5, is affected by means of the feed ropes 25 which are connected to the winding drums 43 to be wound thereon. The drums 43 are suitably mounted upon the main frame and are actuated by ratchet mechanisms 44 connected by the rods 45 to the eccentrics 46 on the power shaft 34. As such winding mechanism is well known in the art, and as its construction forms no part of the present invention, detailed description is not thought to be necessary at this time.

The conveyor 3 is of the well known chain and scraper type and comprises a forward horizontal receiving section resting directly upon the sole plate 2 and extending below the lower boundary planes of the cutter bits 11, a middle upwardly inclined section, and a horizontal delivery section extending rearwardly of the machine, beneath which the car 47 may be placed to receive the coal as it falls from the end of the conveyor. The conveyor consists of an elongated trough 48 composed of suitable plates and angles, along which travels two endless chains 49 joined together at spaced intervals by the scraper crossbars 50 in a manner common in conveyor practice. As the construction of this conveyor forms no part of the present invention further description is not thought to be required at this time. Mounted in bearings supported by the conveyor structure, is a driving shaft 51 having sprocket wheels 52 which engage the return strand of the conveyor chains 49 to drive the conveyor. A sprocket wheel 53 attached to the shaft 51 is connected through a suitable chain 54 with a similar sprocket wheel 55 mounted on the power shaft 34 to drive the conveyor.

At the beginning of each cycle of operation the machine lies along the center line of the mine room with the cutter arms extending forward, their ends in close proximity to each other and to the coal face, and locked against rotation by the pins 28. The feed ropes 25 are drawn out from the drums 43 and attached to suitable anchors 56 placed in advance of the machine, as illustrated in Fig. 4. The motor is started in a direction to cause the cutter chains 10 to travel forwardly along the inner edges and rearwardly along the outer edges of the cutter arms. When the drums 43 are actuated to wind the ropes 25 the machine moves forward and the cutter bits engage the coal to cut it, forming the entering, or sumping, cut, as shown in Fig. 5. When the machine is fully sumped the feed ropes are disconnected from the anchors 56, passed around the outer sides of the sheaves 24 and attached to the projections 30 of the cutter arm yokes, and the pins 28 are removed. When now the ropes 25 are wound the cutter arms 5 will rotate divergently to undercut the coal, finishing the operation as shown in Fig. 6. The motor is then stopped, and the coal is broken down in any preferred manner, as by blasting. The feed ropes 25 are then changed to the inner sides of the sheaves 24 and again attached to the projections 30 of the cutter arm yokes. The motor is then reversed so as to drive the cutter chains forwardly along the outer edges, and rearwardly along the inner edges of the cutter arms 5, the cutting edges of the bits 11 trailing against the coal. The feed mechanisms 44 are then manipulated to wind the ropes 25, rotating the cutter arms 5 convergently, as illustrated in Fig. 7.

The cutter chains 10 and the bits 11 engage the broken coal and drag it onto the conveyor 3 to be carried rearwardly and deposited in the car 47. As the cutting edges of the bits 11 point in the opposite direction to the travel of the chains, they do not take hold of the coal, but tend rather to slip over such fragments as are too firmly embedded in the mass to be easily moved. This action tends to loosen up the coal without the unnecessary production of slack. As the bits pass around the sprocket wheels 9 they readily release themselves from the coal and tend to push it over on to the conveyor. The coal is thus gathered from the floor formed by the cutting bits and transferred to the conveyor, the feeding mechanism being manipulated to accelerate or retard the rate of rotation of the cutter arms as occasion may require.

When the cutter arms 5 have reached the central, or initial position, and all of the broken coal has been loaded, the machine will be lifted bodily by any preferred means, such as by lifting jacks, suitable blocks 57

placed beneath the sole plate 2 as shown in Fig. 8, to allow the machine to slide forward over the bottom formed by the cutting mechanism, and the operation, as above 5 described, repeated.

What I claim is—

1. In a mining apparatus, the combination with a base frame, of a conveyer thereon, a cutter arm pivotally mounted upon 10 said base frame for rotation in a horizontal plane and having cutter elements adapted when said arm is rotated in one direction to cut a kerf in the coal body and when it is rotated in the reverse direction to gather 15 broken coal upon said conveyer.

2. In a mining apparatus, the combination with a base frame, of a conveyer thereon, a cutter arm pivotally mounted upon 20 said base frame for rotation in a horizontal plane and a cutter chain upon the cutter arm adapted to travel in one direction to cut a kerf in the coal body and in the reverse direction to gather broken coal upon 25 said conveyer.

3. In a mining apparatus, the combination with a main frame, of a conveyer thereon, a cutter arm pivotally mounted upon 30 the main frame for rotation in a horizontal plane and a cutter chain on the cutter arm adapted to travel in one direction to cut a kerf in the coal body when the cutter arm is rotated in one direction and to travel in the reverse direction to gather broken coal onto 35 said conveyer when said cutter arm is rotated in the other direction.

4. In a mining apparatus, the combination with a main frame, a conveyer thereon, a cutter arm pivotally mounted upon the main frame for rotation in a horizontal 40 plane, a cutter chain on the cutter arm adapted to travel in one direction to cut a kerf in the coal body when the cutter arm is rotated in one direction and to travel in the reverse direction to gather broken coal 45 upon said conveyer when the cutter arm is rotated in the other direction, and means to rotate the cutter arm in either direction.

5. In a mining apparatus, the combination with a main frame, of a conveyer thereon, a cutter arm pivotally mounted on the main frame for rotation in a horizontal plane, a cutter chain upon the cutter arm having cutter bits inclined to the direction of the cutter chain and adapted to travel in 50 one direction to cut a kerf in the coal body and to travel in the reverse direction to gather broken coal upon the said conveyer.

6. In a mining apparatus, the combination with a main frame, of a conveyer thereon, a cutter arm pivotally mounted upon the main frame for rotation in a horizontal plane, a cutter chain upon the cutter arm having cutter bits inclined in the direction of the cutter chain and adapted to travel 60 in one direction to cut a kerf in a coal body

when the cutter arm is rotated in one direction and to travel in the reverse direction to gather broken coal upon the said conveyer when the cutter arm is rotated in the other direction.

7. In a mining apparatus, the combination with a main frame, of a conveyer thereon, a cutter arm pivotally mounted upon the main frame for rotation in a horizontal plane, a cutter chain upon the cutter arm having cutter bits inclined in the direction of the cutter chain and adapted to travel in one direction to cut a kerf in the coal body when the cutter arm is rotated in one direction and to travel in the reverse direction to gather broken coal onto said conveyer when the cutter arm is rotated in the reverse direction, and means to rotate the cutter arm in either direction.

8. In a mining apparatus, the combination with a main frame, of a conveyer thereon, of two cutter arms pivotally mounted upon the main frame for rotation in the same horizontal plane and adapted when rotated in one direction to cut a kerf in 90 the coal body and when rotated in the other direction to gather broken coal onto the said conveyer.

9. In a mining apparatus, the combination with a main frame, of a conveyer thereon, of two cutter arms pivotally mounted upon the main frame for rotation in the same horizontal plane and adapted when rotated divergently to cut a kerf in the coal body and when rotated convergently to 100 gather broken coal upon said conveyer.

10. In a mining apparatus, the combination with a main frame of a conveyer thereon, of two cutter arms pivotally mounted upon the main frame for rotation in the same horizontal plane, cutter chains on the cutter arms adapted to travel in one direction to cut a kerf in the coal body and in the reverse direction to gather broken coal onto 110 said conveyer.

11. In a mining apparatus, the combination with a main frame, of a conveyer thereon, two cutter arms pivotally mounted upon the main frame for rotation in the same horizontal plane, cutter chains on the cutter arms adapted to travel in one direction to cut a kerf in the coal body when the cutter arms are rotated divergently and to travel in the reverse direction to gather broken coal onto said conveyer when the 115 cutter arms are rotated convergently.

12. In a mining apparatus, the combination with a main frame, of a conveyer thereon, two cutter arms pivotally mounted upon the main frame for rotation in the same horizontal plane, cutter chains on the cutter arms adapted to travel in one direction to cut a kerf in the coal body when the cutter arms are rotated divergently and to travel 125 in the reverse direction to gather coal onto 130

the said conveyer when the cutter arms are rotated convergently.

13. In a mining apparatus, the combination with a main frame, of a conveyer thereon, two cutter arms pivotally mounted upon said main frame for rotation in the same horizontal plane, cutter chains on the cutter arms having cutter bits inclined to the direction of the chains and adapted to travel in one direction to cut a kerf in the coal body and in the reverse direction to gather broken coal onto said conveyer.

14. In a mining apparatus, the combination with a main frame, of a conveyer thereon, two cutter arms pivotally mounted upon the main frame for rotation in the same horizontal plane, cutter chains on the cutter arms having cutter bits inclined to the direction of the chains and adapted to travel in one direction to cut a kerf in the coal body when the cutter arms are rotated divergently and to travel in the reverse direction to gather coal onto said conveyer when the cutter arms are rotated convergently.

15. In a mining apparatus, the combination with a main frame, of a conveyer thereon, two cutter arms pivotally mounted upon the main frame for rotation in the same horizontal plane and cutter chains on the cutter arms having cutter bits inclined in the direction of the cutter chains and adapted to travel in one direction to cut a kerf in the coal body when the cutter arms are rotated divergently and to travel in the reverse direction to gather broken coal onto said conveyer when the cutter arms are rotated convergently, and means to rotate the cutter arms in either direction.

16. In a mining apparatus, the combination of the main frame, the elevating conveyor thereon positioned in the central, vertical, longitudinal planes thereof, the two vertical shafts mounted on the frame at the sides of the conveyor, the sprocket wheels on the shafts, respectively, the forwardly projecting arms mounted to rotate around the axes of said shafts, the forwardly extending chains supported on the arms and engaging with said wheels, and means for driving in common the conveyor and the chains substantially as set forth.

17. In a mining apparatus, the combination of the main frame, the elevating conveyor thereon positioned in the central longitudinal planes thereof and having a relatively low receiving section at the floor and a relatively high delivery section, the two forwardly projecting arms swinging around vertical axes in a transverse plane behind that of the front end of the conveyor, and the endless chains supported on said arms and arranged to bring material to the conveyor while they are positively connected therewith.

18. In a mining apparatus, the combination of the main frame, the conveyor thereon positioned in the central, vertical longitudinal planes thereof, the two horizontally swinging arms respectively mounted on vertical axes at the sides of the conveyor, and endless chains traveling around said axes and around the arms and adapted to positively draw material to points behind the front end of the conveyor.

19. In a coal loading machine, the combination with an elongated conveyor, of gathering mechanism comprising two coal engaging elements adapted to travel along substantially horizontal non-circular orbital paths converging towards the forward end of said conveyor and adapted to engage the coal which is to be loaded and move it onto said conveyor.

20. In a coal loading machine, the combination with two substantially horizontal rotary driving elements, of an elongated conveyor comprising an endless material moving element the forwardly and rearwardly moving parts of which travel in the same vertical planes and having its forward end in a transverse vertical plane in advance of that of the axes of the driving elements, two coal engaging devices for moving loose coal to the forward end of the conveyor respectively actuated by said driving element and traveling on lines converging towards the central vertical longitudinal plane of said conveyor and having orbits or paths of travel in a plane relatively above the plane of the conveyor.

21. In a coal loading machine, the combination with an elongated conveyor, of gathering mechanism comprising two co-operating oppositely moving coal engaging elements adapted to travel in substantially horizontal non-circular converging orbital paths to engage the coal which is to be loaded and move it onto said conveyor.

22. In a coal loading machine, the combination with an elongated conveyor, of gathering mechanism comprising two co-operating oppositely moving coal engaging elements adapted to travel in substantially horizontal non-circular converging orbital paths, and means to bodily move said gathering mechanism relative to the coal which is to be loaded to cause said coal engaging elements to engage said coal to move it onto said conveyor.

23. A conveyer-sweeper structure comprising a sweeper structure that is composed of a pair of sweeper devices that are symmetrically arranged and operative to be swung towards and away from one another by a substantially horizontal movement for operating upon a pile of material that is positioned between said devices and to deliver material from said pile directly in-

wardly from said pile towards the space between the axes of said devices, and an elevating conveyer structure having the receiving end located so as to receive such material from between said axes, whereby said pile serves to position said devices without other positioning means.

In testimony whereof I affix my signature, in the presence of two witnesses.
